UNITED STATES PATENT OFFICE.

ALEXANDER CONSTANTINE IONIDES, JR., OF LONDON, ENGLAND.

GASEOUS-FUEL BURNER.

1,419,054.

Specification of Letters Patent. Patented June 6, 1922.

Application filed October 27, 1919. Serial No. 333,653.

To all whom it may concern:

Be it known that I, ALEXANDER CONSTANTINE IONIDES, Jr., a subject of the King of Great Britain and Ireland, and residing at 5 34 Porchester Terrace, London, W. 2, England, have invented certain new and useful Improvements in or Relating to Gaseous Fuel Burners, of which the following is a specification.

10 This invention relates to the formation of combustible gaseous mixtures from continuous supplies of two elastic fluid constituents, such as gas and air maintained by sensitive pressure balancing appliances at constantly 15 related pressures, said constituents prior to ignition being combined in the correct proportions for complete combustion irrespective of the surrounding elements, upon issue from an open orifice, preferably in a chamber 20 from which the waste products are expelled without the suction generally exerted by a chimney or equivalent device.

In an appliance in which a central column of one gaseous fluid is surrounded by a 25 sheath formed of another gaseous fluid moving in the same direction, and said streams when mingled pass into a combustion chamber, means have been provided for adjusting at the mixing point the area of the port 30 or aperture through which one of the constituents passes and when such port is utilized for the lighter one of two constituents and the burner is of moderate dimensions it will operate satisfactorily over a fair 35 range of pressure variations. Where, however, greater pressure variations are experienced or the size of burner and consequently the areas of the passage-ways are so increased that the ratio of frictional resistance to size of apertures is materially altered, difficulties are experienced which it is 40 the object of the present invention to overcome.

The invention consists in a gaseous fuel 45 combustion appliance for forming a mixture of two fluids as indicated, closely adjacent to the combustion zone, in which said fluids enter a central space through adjacent parallel circumferential port belts, each of adjustable width, and the mixture passes immediately by a diverging orifice into a combustion chamber.

The invention also consists in improvements in or relating to burner and mixing 55 appliances as hereinafter described.

Referring now to the accompanying more or less diagrammatic drawings:

Figure 1 is a longitudinal section through a burner and mixing appliance fitted to a combustion chamber in accordance with the 60 invention;

Figure 2 is a view looking upon the outer end of the burner shown in Figure 1.

In carrying the invention into effect in the convenient form shown by way of example in the drawings, a cylindrical chamber *a* which may be formed entirely as a metal casing where temperatures will permit as in small furnaces, or partly of metal and partly of refractory material as hereinafter 70 more fully described is fitted to a combustion chamber in such a manner that a co-axial orifice *b* in a flat disc *a*⁴ forming the end of the chamber leads by way of a slightly converging or parallel portion *c* to a flared or 75 coned mouthpiece *d* communicating with the combustion chamber *e*.

The chamber *a* is extended for any desired length exterior to the outer face of the wall *f* of the furnace and at its end is provided 80 with an enlargement *a'* in the shape of a shallow bulb having a boss *a*² provided with an internal screw-thread and a branch *a*³ by which one of the gaseous constituents of the mixture, say for example gas, is supplied to 85 the appliance.

Positioned co-axially within the cylindrical chamber *a* is a hollow cylinder *g* having a flat disc end *g'* in which is an aperture *h* co-axial with and preferably slightly smaller 90 than the orifice *b* in the cylindrical chamber *a*, the discs *g'* and *a*⁴ providing between them a parallel sided disc-like passage.

The hollow cylinder *g* is provided at its outer end with a cylindrical screw-threaded 95 portion *i* engaging with threads formed in the boss *a*², and also engaging internal threads in a boss *j* of a second shallow bulb *j*, positioned at a convenient distance behind the bulb *a'* by connecting pieces *k* or any 100 other convenient construction permitting adjustment of the hollow cylinder *g*, may be employed. The bulb *j* is also provided with a branch *j*² for supplying the other gaseous constituents of the mixture, say for example 105 air, to the apparatus.

The cylindrical threaded portion *i* is provided between the two bulbs with an arm *l* by means of which it may be rotated, and the distance between the disc *a*⁴ of the cham- 110

ber *a* and the end *g'* of the hollow cylinder *g* varied, in order to adjust the parallel sided radial disc-like passage-way leading from the annular gas passage into the mouth-piece *c*.

Within the hollow cylinder *g* is a closed tube or solid rod *m* having a flat circular end, by means of which the passage-way through the aperture *h* may be adjusted.

- 10 The tube or rod *m* is supported adjacent to its flat end upon wings or guides *n* for retaining it co-axial with the aperture, and at its other end it is provided with a screwed portion *o* engaging an internal thread in the end of the bulb *j*. At the extreme end of the rod *m* is a squared or similar portion *p* for receiving a key, by means of which the radial passage-way leading to the aperture *h* may be adjusted, which provision in combination with the arm *l* permits adjustment of both port belts without disconnecting the burner or even interrupting combustion.

In burners of large dimensions or where very high temperatures are likely to be experienced, the portion of the cylindrical chamber *a* adjacent to the burner mouthpiece may be formed in the refractory material of the wall itself and the remainder of the chamber may be formed of metal suitably connected thereto. Alternatively, a cylindrical refractory portion may be separately attached to the metal portion of the chamber shell prior to the attachment of the complete element to the furnace wall. The inner part of the hollow cylinder *g* and the end of the rod or tube *m* may also in like manner be formed of refractory material suitably connected to metal portions which are provided in the cooler parts of the apparatus.

Means for obtaining a sample of the mixture may be provided by replacing the rod *m* with a hollow member having a removable plug at its inner end, or a small passage-way 45 may be provided from the flared combustion orifice to the exterior of the furnace wall for this purpose.

Other modifications and additions may also be introduced without in any way departing from the spirit of the invention.

Having now described my invention, what I claim as new and desire to secure by Letters Patent is:—

1. In combination in a gaseous fuel combustion appliance for forming a mixture of two fluids closely adjacent to the combustion zone, a chamber, an orifice opening from the end thereof to a combustion space, a tubular member movable axially to and from said orifice in said chamber and having an end provided with an aperture in line with and adjacent to said orifice, a member within said tubular member complementary to and in line with said aperture and axially movable to adjust the passage of fluid therethrough and

means for supplying the two constituents of a combustible gaseous fluid mixture separately to said chamber and said tubular member.

2. In combination in a gaseous fuel combustion appliance for forming a mixture of two fluids closely adjacent to the combustion zone, a chamber having a disc end, an orifice in said end opening to a combustion space, a tubular member movable longitudinally in said chamber and having an end provided with an aperture co-axial with and adjacent to said orifice, a disc complementary to said aperture adjustably positioned coaxial therewith to adjust the flow of fluid therethrough, means for supplying a light fluid such as gas to said chamber and means for supplying a heavier fluid such as air to said tubular member.

3. In combination in a gaseous fuel combustion appliance for forming a mixture of two fluids closely adjacent to the combustion zone, a chamber having a disc end, an orifice in said end, a short passage flared at its further end leading from said orifice to a combustion space, a tubular member movable longitudinally in said chamber and having an end provided with an aperture co-axial with and adjacent to said orifice, a disc complementary to said aperture adjustably positioned coaxial therewith to adjust the flow of fluid therethrough, and means for supplying the two constituents of a combustible gaseous fluid mixture separately to said chamber and said tubular member.

4. In combination in a gaseous fuel combustion appliance for forming a mixture of two fluids closely adjacent to the combustion zone, a cylindrical chamber, a hollow cylinder axially movable therein, and providing a surrounding annular space, connections for supplying one constituent of the mixture to said annular space and the other to said hollow cylinder, a central orifice in a disc forming the end of said cylindrical chamber, a flared mouthpiece leading from said orifice into a combustion space, an end to said hollow cylinder in the form of a disc coaxial with said before mentioned disc and adapted by movement of said cylinder to regulate the passage of gaseous fluid to said orifice from said annular space, an aperture in the disc forming the end of said hollow cylinder not larger than said orifice and opposite thereto, and a third disc supported within said hollow cylinder opposite to said aperture and movable to regulate the passageway therethrough.

5. In combination in a gaseous fuel combustion appliance for forming a mixture of two fluids closely adjacent to the combustion zone, a chamber, an orifice opening from the end thereof to a combustion space, a tubular member movable axially to and from said orifice in said chamber and having an end

provided with an aperture in line with and adjacent to said orifice, a member within said tubular member complementary to and in line with said aperture and axially movable to adjust the passage of fluid therethrough, an enlargement at the end of said chamber remote from said orifice, an inlet branch for admitting a fluid such as combustible gas to said enlargement, a casing adjacent to said enlargement, an inlet branch for admitting a fluid such as air to said casing, screw-threaded apertures at the end of said enlargement and in the adjacent side of said casing through which said tubular member projects, screw-threads on said tubular member complementary to said threaded apertures, 40 a rod projecting from said member movable in said tubular member extending through the ends of said casing and co-operating screw-threads in said casing and upon said rod for effecting axial adjustment thereof. 45

5. In combination in a gaseous fuel combustion appliance for forming a mixture of two fluids closely adjacent to the combustion zone, a chamber, an orifice opening from the end thereof to a combustion space, a tubular member movable axially to and from said orifice in said chamber and having an end 20 provided with an aperture in line with and adjacent to said orifice, a member within said tubular member complementary to and in line with said aperture and axially movable to adjust the passage of fluid therethrough, 25 an enlargement at the end of said chamber remote from said orifice, an inlet branch for admitting a fluid such as combustible gas to

35 said enlargement, a casing adjacent to said enlargement, an inlet branch for admitting a fluid such as air to said casing, screw-threaded apertures at the end of said enlargement and in the adjacent side of said casing through which said tubular member projects, screw-threads on said tubular member complementary to said threaded apertures, 40 a rod projecting from said member movable in said tubular member extending through the ends of said casing and co-operating screw-threads in said casing and upon said rod for effecting axial adjustment thereof. 45

6. In combination in a gaseous fuel combustion appliance for forming a mixture of two fluids closely adjacent to the combustion zone, a conduit leading to a combustion space, an abrupt and considerable restriction reducing the end of the latter portion of said conduit, a tubular member having at one end a constricted aperture axially movable in said conduit with said aperture adjacent and in line with said restriction, an 50 adjusting stopper complementary to said aperture movable axially in line therewith in said tubular member and means for supplying the two constituents of a combustible gaseous fluid mixture separately to said conduit and said tubular member. 55

In testimony whereof I have signed my name to this specification.

ALEXANDER CONSTANTINE IONIDES, Jr.
